(57) **CLAIM**

The design of a package, as shown and described.

DESCRIPTION

FIG. 1 is a top, front, right perspective view of a package according to a first embodiment of our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dashed line portions of the figure drawings, including the binding, zipper, handle and bedding article inside the package system, are included to show unclaimed subject matter only and forms no part of the claimed design. In a preferred embodiment, the nature of this product is a package for bedding articles.
